(57) **CLAIM**

The ornamental design for a post-curing chamber, as shown and described.

DESCRIPTION

FIG. 1 illustrates a right-side elevated perspective view of a post-curing chamber;

FIG. 2 illustrates a left-side elevated perspective view thereof;

FIG. 3 illustrates a front view thereof;

FIG. 4 illustrates a posterior view thereof;

FIG. 5 illustrates a top view thereof;

FIG. 6 illustrates a bottom view thereof;

FIG. 7 illustrates a right-side view thereof;

FIG. 8 illustrates a left-side view thereof;

FIG. 9 illustrates a right-side elevated perspective view, showing a lid-opened state thereof;

FIG. 10 illustrates a left-side elevated perspective view, showing a lid-opened state thereof; and

FIG. 11 illustrates a top view, showing a lid-opened state thereof;

FIG. 12 illustrates a bottom view, showing a lid-opened state thereof;

FIG. 13 illustrates a right-side view, showing a lid-opened state thereof;

FIG. 14 illustrates a left-side view, showing a lid-opened state thereof; and,

FIG. 15 illustrates a left-side perspective exploded view, showing a lid-opened state with the inner tray removed for ease of illustration.

The broken lines shown represent portions of the post-curing chamber that form no part of the claimed design.

1 Claim, 15 Drawing Sheets
